UNITED STATES PATENT OFFICE.

WILLIAM SCHRODER, OF COVINGTON, KENTUCKY, ASSIGNOR TO THE SEBASTIAN LATHE COMPANY, OF CINCINNATI, OHIO, A CORPORATION OF OHIO.

FASTENING DEVICE.

Application filed October 22, 1924. Serial No. 745,246.

This invention relates to a clamp or supporting device as an article of manufacture, adapted for suspending catch pans or like receptacles to frame structures of various kinds. More particularly, a specified use is in attaching chips or water pans to the supporting frames of lathes or machine tools so as to sustain the pans beneath the beds of the machines.

10 An object of the invention is to provide a device having a fastening portion adapted to be secured to the machine support, and having a foot or supporting shelf extending out therefrom so as to engage under the pan being supported, and a clamping block or jaw adjustable in relation to the fastening portion so as to clamp the rim of the element being supported against the fastening member of the device and in position on the foot or supporting shelf.

15 Another object is to provide a device of this character which can be cheaply manufactured and can be quickly and conveniently attached to a machine frame so as to securely sustain a receptacle beneath the machine, permitting easy removal of the receptacle for the purpose of cleaning.

20 Still another object is to provide a fastening device having a pair of jaws adapted to clampingly engage about the rim of the receptacle to be supported, one of said jaws adjustable in relation to the other so as to permit the insertion and securing of various receptacle rim thicknesses between the jaws.

25 Other objects and certain advantages will be more fully set forth in the description of the accompanying drawings forming a part of this specification, in which:

30 Figure 1 is a side elevation of a plurality of the clamps illustrating the clamps in set up position attached to the legs of the lathe, and having a receptacle supported and secured thereon.

35 Figure 2 is a sectional view taken on line 2—2 Figure 1, further illustrating the clamps in service position.

40 Figure 3 is a detail side view of the clamp partly in section, showing the clamp as attached to the leg of a lathe, and a receptacle supported and secured in the clamp.

45 Figure 4 is a sectional view taken on line 4—4, Figure 3, showing the clamp in front view.

50 In illustrating the invention, a plurality of the clamps or supporting devices have

been shown as supporting a chip pan 1 beneath the bed of a machine tool, the supporting devices being clamped to the legs 2 of the machine tool.

The device as illustrated in detail in Figures 3 and 4, comprises a body portion 9 and an inclined supporting leg 10 integral with and extending from the body portion, the body portion being suitably formed to adapt it for attachment to the legs of the machine tool. The lower end of the leg portion is provided with an annular foot extension 11 adapted to engage beneath the pan 2 and to support the same. The pan side or rim is held against the inclined face 12 of the leg 10 by means of a clamping jaw 13 adapted to engage the inside of the rim, and to clamp the rim against the leg. The adjusting of the clamping jaw 13 is accomplished by means of a screw 14. The leg portion functions herein as a stationary clamping jaw in conjunction with the clamping jaw 13. The movable jaw consists of a plate engaged at its upper side against a raised portion of the face 12, providing a space between the low portion of the face 12 and the plate 13, for the reception of the particular pan top edge. The plate is loosely traversed by the screw 14, the screw being threaded into the inclined leg at a point slightly below the raised portion.

55 The body of the device comprises a pair of jaws 15 formed by a slot 16. This slot is in vertical position as the device is viewed in set up position, and screws 17 are threaded into one of the jaws at right angles to the slot, the screws traversing the slot so as to engage the portion of the lathe leg inserted between the jaws, securing the same between the screw points and the opposite wall of the slot.

60 The relation of the slot and jaws to the pan engaging portion 12 of the device, allow the adjustment of the leg 10 to any desired inclination to suit the pan rim inclination, and permits the clamping device to be swung down to disengage from the pan when the clamping jaw 13 is loosened. The adjustable jaw 13 adapts the device for clamping various thicknesses of pan rims therein, and securely maintains the pan in set position on the foot extension 11.

65 Having described my invention, I claim:

70 1. A device of the class described comprising a body portion slotted at one side to 110

provide spaced jaws adapted for engagement with or about a portion of a support and having a leglike extension providing a flat face lying in a plane at right angles to the long axis of the slot, said leg terminating in an angular foot for supporting the receptacle at the bottom and a clamping jaw adapted for cooperation with the upper edge of the receptacle supported by the leg and foot, to force the receptacle against the leg, and clamping elements for the jaws.

2. A device of the class described, having

a pair of angularly related jaws at substantially opposite sides thereof, one pair for engagement about a support and the other 15 for engagement about the top edge of a receptacle, said device having a leg extending in a direction away from the receptacle engaging jaw, said leg having a terminal foot for supporting the bottom of the receptacle 20 while the upper edge is clamped by the jaw.

In witness whereof, I hereunto subscribe my name.

WILLIAM SCHRODER.
